UNITED STATES PATENT OFFICE.

WILLIAM HENRY FITCH, OF ALLENTOWN, PENNSYLVANIA.

BURNER.

Application filed November 22, 1923. Serial No. 676,248.

This invention relates to a burner for firing fuel in pulverized form, which is adapted for use in connection with furnaces generally, such as stationary boiler furnaces, metallurgical furnaces, cement kilns, etc., although it has been found of particular value as a burner for metallurgical furnaces in which intensely high heat or, in other words, high CO₂ is developed.

10 The burner is designed to produce a short flame of low velocity and high heat intensity and to prevent an accumulation of partly burned fuel or coke about the discharge orifice of the burner. Difficulty with coking about the discharge orifice is a common fault with the present type of burners in use for firing pulverized fuel, the coke forming about the burner orifice and building up to an extent which results eventually in the 20 restriction or virtual closing up of the orifice. This necessitates cleaning out the burner periodically which is a troublesome operation and furthermore, cannot be done without a temporary suspension of operation. 25 Moreover, pulverized fuel burners, as heretofore designed, and used in practice, provide in themselves no means of regulating the velocity of the mixture of pulverized fuel and air which they feed to the furnace; or if this is arranged for at all, the means employed have been ineffectual to 30 accomplish the desired results. Generally speaking, such burners are designed to produce a combustible mixture of fuel and air 35 by adding to the fuel and primary air, or carrier air for conveying the fuel into the furnace, a certain amount of secondary air to obtain better mixture and to furnish additional air required for combustion. The 40 secondary air is usually brought into the burner mixing chamber by induction caused by the jet of fuel and primary air. In order that the necessary amount of fuel may be introduced to create the high heat required, as for example, in metallurgical furnaces, the mixture of fuel and air must be introduced into the furnace at high velocity. Such a jet produces a long flame with consequent wide distribution of heat of lesser 45 intensity and impingement of the flame on the opposite wall of the furnace with resultant destruction of the refractories.

50 The burner constituting the present invention comprises a chamber having the usual discharge orifice from which the mixture of fuel and air issues. Extending

through the chamber, and in alignment with the discharge orifice, is a feed pipe for conveying the mixture of fuel and primary air through the chamber for projection out of 60 the discharge orifice. The primary air, it will be understood, is air under pressure, or an air blast, customarily supplied by a fan, and this air serves to carry the fuel in suspension through the feed pipe in the burner 65 chamber and thence into the furnace. The burner is provided with means for admitting into the chamber a supply of secondary air which is preferably, also, air under pressure. Means are provided in the burner, preferably in the form of a valve of approximately conical formation, which is capable of being moved toward and away from the discharge orifice of the burner chamber.

70 The secondary air is constrained by the valve, and the walls of the chamber surrounding the discharge orifice, to flow into the path of the jet of fuel and primary air, and it will be readily seen that where this secondary air is under pressure a very thorough mixture of fuel and air is obtained in the burner before discharge from the outlet orifice thereof. Furthermore, by adjustment of the valve toward and away from the discharge orifice, the velocity as well as the 75 volume of the secondary air entering the jet of fuel and primary air is controlled in accordance with the velocity of the latter stream and the requirements of combustion. For example, where large quantities of fuel 80 are being consumed and the mixture of the fuel and primary air is in consequence being projected at relatively high velocity the valve is adjusted toward its extreme open 85 position so that greater quantities of secondary air are added as combustion air, needed to consume the increased quantity of fuel; but where a small quantity of fuel is being consumed, the valve is adjusted toward the discharge orifice to obtain a 90 correspondingly smaller supply of secondary air for combustion. Under either extreme or intermediate conditions of operation, the valve is adjusted in accordance 95 with the requirements. An important feature of operation, however, is that the secondary air, especially where under pressure, and directed against the fuel and primary air stream, as described, cuts down the velocity thereof and the resultant fuel and air stream issuing from the discharge orifice is 100 considerably reduced in velocity. Thus 105 110

projected into the furnace, the fuel mixed with air entering at a reduced velocity produces a relatively short intensely hot flame with concentration or localization of heat 5 and elimination of impingement on the walls of the furnace. The direction of the secondary air against the issuing fuel jet mixed with primary air, furthermore, ensures thorough mixture of the fuel and air 10 within the burner prior to its injection into the furnace and also by virtue of its velocity and impingement against the inner walls of the chamber, prevents lodging and accumulation of fuel around the burner opening 15 and consequently the formation of coke. The form of burner at present preferred is illustrated in the accompanying drawing, wherein the burner is shown positioned in the wall of the furnace which is simply indicated. 20

Referring to the drawing, the burner includes a casing 1 forming a chamber provided with a discharge orifice 2 at one end thereof, and is shown positioned in the opening 3 of the furnace wall 4. In alignment with the orifice 2 and extending through the chamber 1 is a supply or feed pipe 5 into which fuel and the primary or carrier air are introduced, from sources not shown, but 25 which arrangements are well understood. The lower portion of the chamber 1 is provided with an extension 6 which provides the connection to the source of the secondary air supply, also not shown, but likewise well understood. 30 The primary air supply or carrier air for the fuel introduced into the feed pipe 5 is usually supplied by a centrifugal fan and the inlet 6 for secondary air is also preferably connected to a source of air supply 35 under pressure which may be a centrifugal fan. Mounted on the feed pipe 5 is a valve 7 having an integral sleeve portion 8 which fits over the feed pipe 5 and is adapted to slide thereon. The lower part of the 40 sleeve portion 8 is formed with rack teeth 9 which are adapted to be engaged by a pinion 10 mounted on a shaft 11. The shaft 11 is supported in the walls of the casing or 45 chamber 1 and at its outer end carries a hand wheel 12 by which the valve member is 50 adjusted.

The head portion of the valve is of approximate conical formation and is hollow as at 13 primarily to reduce its weight. 55

The valve head forms the incoming secondary air in the chamber 1 in a hollow conical body which is constrained by the valve and the confining walls of the chamber 1 to intersect at an angle the fuel and 60 primary air issuing from the feed pipe 5. The valve is adjustable by the mechanism provided, toward and away from the outlet opening 2 in accordance with the requirements of combustion, and the space between 65 the face of the valve and the walls of the

chamber serves as a small mixing chamber in which the secondary air flowing around the edges of the valve mingles with the fuel and air mixture passing outward through the opening in the valve. Owing to the angle at which the secondary air intersects the stream of fuel and primary air, a thorough mingling of the air and fuel is brought about in this mixing chamber, and the size of the mixing chamber and the effectiveness 75 of the mixing action can be controlled by moving the valve and thus varying the angle at which the streams intersect. It will be seen also that the secondary air passing around the valve head 7 provides a constantly moving body of air in contact with the inside wall of the casing 1 about its outlet orifice 2, the velocity of this moving body of air depending upon the adjustment of the valve and the accumulation of fuel 80 about the orifice with consequent coking is thus prevented. It has been found in practice that the burner described in the foregoing will produce a most excellent mixture of fuel and air and a short intensely hot 85 flame without coking difficulties as before noted, and the CO_2 obtainable has been in the neighborhood of $15\frac{1}{2}$ to 16%.

I claim:

1. A burner for pulverized fuel comprising 95 a casing having an outlet opening in one wall thereof, a feed pipe for delivering a mixture of pulverized fuel and air, this pipe terminating in the casing in alignment with the opening and at a distance therefrom, a valve 100 member mounted on the pipe within the casing and adjustable toward and away from the opening, this valve member having a diameter greater than that of the outlet opening in the casing wall, and having a passage formed through it of substantially the same diameter as that of the feed pipe, the fuel and air mixture discharging from the feed pipe and passing 105 through this passage to flow through the outlet opening of the casing, and means for introducing into the casing an additional supply of air which mingles with the fuel and air mixture passing out of the valve member between the face of the latter and 110 the outlet opening of the casing.

2. A burner for pulverized fuel comprising 115 a casing having an outlet opening in one wall thereof, a feed pipe for delivering a mixture of pulverized fuel and air, this pipe terminating in the casing in alignment with the opening and at a distance therefrom, a valve member mounted on the pipe 120 within the casing and adjustable toward and away from the opening, this valve member having a diameter greater than that of the outlet opening in the casing wall, and having a passage formed through it of substantially the same diameter as that of the feed pipe, the fuel 125

and air mixture discharging from the feed pipe and passing through this passage to flow through the outlet opening of the casing, and means for introducing an additional supply of air to the casing at a point behind the valve member, the air so supplied being deflected outwardly toward the walls of the casing by the valve member and flowing past the latter in the form of an annular stream which joins the stream of the fuel and air mixture between the valve member and the outlet opening.

3. A burner for pulverized fuel comprising a casing having an outlet opening in one wall thereof, a feed pipe for delivering a mixture of pulverized fuel and air, this pipe terminating in the casing in alignment with the opening and at a distance therefrom, a valve member of larger diameter than the outlet opening mounted on the end of the pipe within the casing and with the walls of the casing defining a mixing chamber between it and the outlet chamber, this valve member having a passage through it of substantially the same diameter as the feed pipe through which the fuel and air mixture from the feed pipe is discharged into the mixing chamber and means for admitting an additional supply of air into the casing at a point such that this additional air flows around the valve member and into the said mixing chamber, mingling with the stream of fuel and air issuing from the valve member and passing with that stream out of the outlet opening.

4. A burner for pulverized fuel comprising a casing having an outlet opening in one wall thereof, a feed pipe for delivering a mixture of pulverized fuel and air, this pipe terminating in the casing in alignment with the opening and at a distance therefrom, a valve member of larger diameter than the outlet opening mounted on the end of the pipe within the casing and with the walls of the casing defining a mixing chamber between it and the outlet opening, the valve member being mounted for adjustment toward and away from the outlet opening to vary the size of this mixing chamber, and having a passage through it of substantially the same diameter as the feed pipe through which the mixture of fuel and air issuing from the feed pipe is discharged into this mixing chamber, and means for introducing an additional supply of air into the casing at a point such that the additional air flows around the valve member and into the mixing chamber, where it mingles with the fuel and air mixture and with the latter passes out through the outlet opening.

5. A burner for pulverized fuel comprising a casing having an outlet opening in one end wall thereof, a feed pipe projecting

through the other end wall and terminating within the casing, this feed pipe being in alignment with the outlet opening and adapted to deliver a mixture of pulverized fuel and air, means for introducing an additional supply of air into the casing, and a valve member interposed between the outlet opening and the point at which this additional supply of air is introduced, this valve member having a greater diameter than the outlet opening and having a passage therethrough of substantially the same size as the feed pipe, the fuel and air mixture issuing from the feed pipe flowing through this passage and being discharged from the latter into the casing in alignment with the outlet opening.

6. A burner for pulverized fuel comprising a casing having an outlet opening in one end wall thereof, a feed pipe projecting through the other end wall and terminating within the casing, this feed pipe being in alignment with the outlet opening and adapted to deliver a mixture of pulverized fuel and air, means for introducing an additional supply of air into the casing, a valve member interposed between the outlet opening and the point at which this additional supply of air is introduced, this valve member having a greater diameter than the outlet opening and having a passage therethrough of substantially the same size as the feed pipe, the fuel and air mixture issuing from the feed pipe flowing through this passage and being discharged from the latter into the casing in alignment with the outlet opening, and means for adjusting the valve member toward and away from the outlet opening.

7. A burner for pulverized fuel comprising a casing having a discharge opening, a feed pipe extending into the casing in alignment with the opening and terminating at a distance therefrom, this pipe being adapted to deliver a mixture of pulverized fuel and primary air, a cone-shaped valve member within the casing having a flat base lying in opposition to the opening, the base being of greater diameter than the opening, and this valve member having a passage through it of substantially the same diameter as the feed pipe through which the mixture of pulverized fuel and air issuing from the feed pipe flows in its passage to the discharge opening, and means for admitting a supply of additional air into the casing at a point to the rear of the valve member, the additional air flowing along the inclined surfaces of the latter and around the edge of the base in the form of an annular stream surrounding the stream of pulverized fuel and air, the two streams mingling between the base of the valve member and the outlet opening.

8. A burner for pulverized fuel comprising

ing a casing having a discharge opening, a feed pipe extending into the casing in alignment with the opening and terminating at a distance therefrom, this pipe being adapted to deliver a mixture of pulverized fuel and primary air, a cone-shaped valve member within the casing having a flat base lying in opposition to the opening, the base being of greater diameter than the opening, and this valve member having a passage through it of substantially the same diameter as the feed pipe through which the mixture of pulverized fuel and air issuing from the feed pipe flows in its passage to

the discharge opening, means for admitting 15 a supply of additional air into the casing at a point to the rear of the valve member, the additional air flowing along the inclined surfaces of the latter and around the edge of the base in the form of an annular stream 20 surrounding the stream of pulverized fuel and air, the two streams mingling between the base of the valve member and the outlet opening, and means for adjusting the valve member toward and away from the opening. 25

In testimony whereof I affix my signature.

WILLIAM HENRY FITCH.
